CLAIM

The ornamental design for a stroller, as shown and described.

DESCRIPTION

FIG. 1 is a perspective view of a stroller in accordance with my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the stroller in use. The broken lines on the stroller illustrate stitching and form part of the claimed design. The drink and snack tray accessory shown in broken lines viewed in FIG. 8 forms no part of the claimed design.

1 Claim, 8 Drawing Sheets(56)
